(57) **CLAIM**

The ornamental design for a bottle with monkey shape, as shown and described.

DESCRIPTION

FIG. 1 is a top, front and left side perspective view of a bottle with monkey shape showing my new design;

FIG. 2 is a top plan view thereof;

FIG. 3 is a bottom plan view thereof. The broken lines in FIG. 3 are included for the purpose of illustrating a portion of the bottom that forms no part of the claimed design;

FIG. 4 is a front elevation view thereof;

FIG. 5 is a rear elevation view thereof;

FIG. 6 is a left side elevation view thereof; and,

FIG. 7 is a right side elevation view thereof.
